VACUUM CIRCUIT BREAKER

Application filed June 23, 1928. Serial No. 287,805.

- Our invention relates to circuit breakers and particularly to enclosed circuit breakers in which the contacts thereof are separated in a vacuum.
- 5 An object of our invention is to provide a circuit breaker of the vacuum type wherein access to the interior of the circuit-breaker housing for the purpose of inspection or repair may be conveniently obtained and 10 wherein the construction of the circuit-breaker housing is compact and inexpensive.
- A further object of our invention is to provide a circuit breaker of the vacuum type wherein the operating mechanism for the 15 circuit breaker extends through an opening in the casing and wherein the opening is sealed by means of a sylphon that is connected to the circuit-breaker operating mechanism in such manner that it is moved laterally by the operating mechanism, as distinguished from a sylphon that is stretched longitudinally by the operating mechanism usually employed in vacuum circuit breakers.
- 20 A further object of our invention is to provide a circuit breaker of the vacuum type wherein the circuit-breaker operating member is pivotally mounted on the circuit-breaker housing and wherein the opening through which the operating member extends, is sealed by means of a sylphon connected to the housing and to the operating member and laterally displaceable by the operating member in order to minimize deflection of the walls of the sylphon and to 25 obtain a maximum opening movement of the circuit breaker contacts.
- These and other objects that will be made apparent throughout the further description of our invention are attained by means of 30 the apparatus hereinafter described and illustrated in the accompanying drawings, wherein
- Fig. 1 is a side view of a circuit breaker embodying features of our invention, and 35 Fig. 2 is a longitudinal section through the circuit breaker shown in Fig. 1, taken on the line II-II thereof.
- Referring to the drawings the circuit breaker apparatus comprises a metal housing 3 provided with a metal cover 4 that
- is welded at 5 to the side walls of the housing. The cover 4 is provided with an opening 6 through which the stationary contact member 7 of the circuit breaker extends into the housing. The contact member 7 is supported upon a conducting rod 8 that is secured to a cover plate 9 which serves to close the opening 6. The rod 8 is provided with a terminal 11 to which one of the conductors, (not shown), may be connected in the usual manner.
- 55 The cover 9 is insulated from the cover 4 by means of a porcelain or glass insulating bushing 12, and a non-rigid seal is provided between the plates 9 and 4 for preventing injury to the bushing by inserting lead packing washers 13 and 14 between the said plates and the ends of the insulating bushing. Flexible annular flanges 15 and 16 are soldered to the ends of the insulating bushing and to the plates 9 and 4, respectively, in which annular grooves 20 are provided for receiving the solder thus forming a gas-tight closure for the opening 6 in the housing, and insulating the stationary contact 60 member 7 from the housing.
- 65 A movable contact member 17 is mounted upon an operating member 18 that is pivotally carried by a bracket 19 having an annular flange 21 welded to the side wall of the housing 3. The operating member 18 extends through the opening 22 that is partially closed by the bracket 19 and is provided with a threaded socket 23 for receiving the threaded end of an insulating operating arm 70
- 75 24. A flange sleeve 25 is welded to the operating member 18, and the opening 22 is sealed by means of a metal sylphon or bellows 26 that is welded to the bracket collar 21, at one end, and to the flanged sleeve 25 at the other end, thus making a gas-tight joint at the place of emergence of the operating member from the casing 3.
- 80 A flexible conductor 27 is clamped, at one end, to the contact member 17 by means of a clamp 28 and, at the other end, to a terminal 29 by means of a clamp 31. It will be noted that the terminal 29 is conductively connected to the housing which may be grounded, if desired.
- 85 90 95 100

The condition of the contacts may be determined by viewing them through a glass window 32 that serves to close an opening 33 in the housing 3. A flanged bushing 34 is welded to the casing 3, and the window 32 is supported by the packing gasket 35 that are retained in place by a metal ring 36 and screw clamps 37 having adaptable screws 38 engaging the outer face of the flange of the bushing 34.

10 Vents 30 and 30^a are provided in the covers 9 and 4, respectively, which establish communication between the interior of the housing 3 and the space between the packing washers 13 and 14, respectively, and the flexible flanges 15 and 16, respectively, for balancing the pressure on both sides of the washers and relieving them from stresses incident to the low pressure within the housing.

15 The cover 9 is retained in position by stud bolts 10 threaded into lugs 10^a and the bolts 10 are surrounded by insulating bushings 10^b that extend through openings in the cover 9 and insulating spacing bushing 10^c. The cover 9 is, therefore, insulated from the cover 4.

20 It will be understood that it is desirable to maintain a vacuum in the the order 30 of .001 millimeters or less of mercury within the casing at all times. Ordinarily, the metal housing will be made sufficiently tight against leakage to maintain the vacuum, but, when desirable, any suitable exhaust 25 means, such a vacuum pump or a vaporizable chemical "getter", may be provided to assist such maintenance.

25 It has been found that the bombardment of electrons emanating from the electrodes or contacts or conductors thereof detrimentally affect the lead gaskets 13 and 14 because the distance between the contact conductors 8 and the inner edges of the gaskets 13 and 14 is greater than the mean free path of the electrons. When electrons are discharged in a container wherein a rare atmosphere is maintained, and are permitted to move unobstructed, their velocities become exceedingly high, and when they have been permitted to 30 move substantially through their mean free path, their collision with molecules of the atmosphere is practically certain to cause further electrons to be released. The released electrons move at terrific velocities. 35 When such electrons strike a metal surface, the molecules at the immediate surface are also exploded and the metal vaporized. The electrons discharged from the conductor, if they do not collide with molecules of the atmosphere, collide with the walls of the container at high destructive velocity and cause volatilization of the metal. Vaporized metal released from the gaskets and elsewhere in the casing, ordinarily, is deposited 40 upon the inner surfaces of the insulator bush-

ing and reduces the insulating qualities thereof.

Disintegration of the lead gaskets and the deposit of metal on the insulating bushing may be avoided by preventing the electrons from obtaining damaging velocities in the vicinity of the lead gaskets, through the expedient of mounting an iron shield 39 in the form of a spool within the insulating bushing 12, the lower flange 41 thereof, being clamped between the cover 4 and the lead gasket 14 and insulated from the conducting rod 8, thereby shielding the gaskets and insulating bushing from the moving electrons. The distances between the cylindrical portion of the shield and the conducting rod 8 and between the end portion of the shield and cover 9 are considerably less than the mean free path of the electrons. It has been found that the interference afforded by the shield prevents numerous collisions with the molecules of the atmosphere within the container and the attaining of destructive velocities and protects the lead gaskets from the bombardment of electrons, thereby preventing deposit of metal upon the interior of the insulator bushing 12.

It will be noted that, by reason of the construction herein illustrated and described, considerable movement may be imparted to 95 the contact 17 for opening the circuit, with a minimum deflection of the bellows walls and, consequently, the life of the bellows is materially increased.

While we have illustrated but one embodiment of our invention, it will be apparent to those skilled in the art that various changes, modifications, substitutions, additions and omissions may be made in the apparatus illustrated without departing from 105 the spirit and scope of our invention, as set forth in the appended claims.

We claim as our invention:

1. A vacuum circuit breaker comprising a housing for containing a rarefied atmosphere, a contact member within the housing, a movable switch member within the housing for engaging the contact member and extending exteriorly thereof through an opening in the housing, a bracket for pivotally supporting the switch member at a point exterior of the housing and attached to the housing, and a flexible sylphon closure for the opening disposed exterior of the housing and surrounding the pivot and constituting 110 a gas seal between the switch member and the housing and permitting pivoted movement of the switch member.

2. A vacuum circuit breaker comprising a metal housing having an opening therein, a contact member within the housing, a conducting member for the contact member extending through the said opening, a closure for the opening for supporting the conducting member, an insulating bushing surround- 125

ing the conducting member for supporting the closure and for insulating the closure from the housing, a second contact member conductively connected to the housing for co-operating with the first contact member, and a metal shield surrounding the conducting member and insulated therefrom and disposed between the conducting member and the interior of the said bushing for intercepting electrons discharged from the said conducting member.

3. A vacuum circuit breaker comprising a metal housing having an opening therein, a contact member within the housing, a conducting member for the contact member extending through the said opening, a closure for the opening for supporting the conducting member, an insulating bushing surrounding the conducting member for supporting the closure and for insulating the closure from the housing, non-rigid metal washers disposed between the ends of the bushing and the housing and closure member respectively, means insulated from the closure member for clamping the closure in operative relation to the housing, a second contact member conductively connected to the housing for co-operating with the first contact member, and a metal shield surrounding the conducting member for intercepting the electrons discharged from the conducting member and preventing the collision of the electrons with the said washers.

4. A vacuum circuit breaker comprising a metal housing having a contact member conductively connected thereto and provided with an opening, a cover for the opening, an insulating cylindrical bushing aligned with the opening and disposed between the cover and the housing, malleable metal sealing washers disposed at the ends of said bushing and constituting a gas-tight seal between the bushing and the housing and cover, respectively, a second contact member conductively carried by the cover and extending through the said bushing, and a cylindrical shield insulated from and surrounding the second contact and having a flange at its innermost end clamped between the innermost washer and the housing for intercepting the electrons discharged from the second contact member and preventing their collision with the interior of said bushing and the said washer.

55 In testimony whereof, we have hereunto subscribed our names this 15th day of June, 1928.

RUDOLF HELLMUND.
ROBERT C. DICKINSON.
